DESIGN FOR A COMBINED NEEDLE THREADER AND NEEDLE CARD HOLDING DEVICE

Samuel A. de Waltoff, Los Angeles, Calif., as-
signor to Deleit Enterprises, Inc., Los Angeles,
Calif., a corporation of California

Application June 22, 1945, Serial No. 120,264

Term of patent 14 years

(Cl. D3—19)

To all whom it may concern:

Be it known that I, Samuel A. de Waltoff, a citizen of the United States of America, residing at Los Angeles, in the county of Los Angeles and State of California, have invented a new, original, and ornamental Design for a Combined Needle Threader and Needle Card Holding Device, in which the following is a specification, reference being made to the accompanying drawing, forming a part thereof, in which

Figure 1 is a front elevational view of a combined needle threader and needle card holding device, embodying my new design.

Figure 2 is an end elevational view of the com-

bined needle threader and needle card holding device shown in Fig. 1,

Figure 3 is a rear elevational view thereof,

Figure 4 is a top plan view thereof,

Figure 5 is a sectional view taken on line 5—5 of Figure 1, and

Figure 6 is a sectional view taken on line 6—6 of Figure 2.

I claim:

The ornamental design for a combined needle threader and needle card holding device, as shown.

SAMUEL A. DE WALTOFF.
